UNITED STATES PATENT OFFICE.

THOMAS A. NAYLOR, OF BALTIMORE, MARYLAND, ASSIGNOR, BY MESNE ASSIGNMENTS, TO RAILWAY STEEL SPRING COMPANY, A CORPORATION.

CONSTRUCTION OF FIREPROOF FLOORS, &c.

SPECIFICATION forming part of Letters Patent No. 727,187, dated May 5, 1903.

Application filed June 4, 1901. Serial No. 63,114. (No model.)

To all whom it may concern:

Be it known that I, THOMAS A. NAYLOR, a citizen of the United States of America, and a resident of 1116 Park avenue, city of Baltimore, State of Maryland, have invented certain new and useful Improvements in the Construction of Fireproof Floors and Similar Structures, of which the following is a specification.

10 My invention relates to new and useful improvements in the construction of fireproof floors and similar structures; and the object thereof is to improve the construction now employed and reduce the cost thereof. In the 15 system of building now commonly employed the space between the I beams or girders which support the load is built in with some sort of fireproof material, such as concrete. The fireproof material has little or no strength 20 in itself and merely increases the load carried by the girders. In my improved construction I substitute for the heavy load of fireproof material carried between the girders a comparatively light metallic structure. By 25 means of this construction not only is the load carried by the girders decreased, but the floors do not require as much vertical height as with the ordinary construction, thus saving wall-space.

30 Referring to the drawings, in which like characters of reference note corresponding parts, Figure 1 is a view taken at right angles to Fig. 2, showing the girders in cross-section and the U-shaped ribs in side elevation. Fig. 35 2 is a sectional view through a floor, showing the U-shaped ribs and the cover-plates in cross-section.

1 designates the ordinary I-girders, upon which the floor is supported.

40 2 designates ribs, which are U-shaped in cross-section and which are suitably fastened to and supported upon the I-girders. As I have shown these ribs they consist of a bottom part 3 and sides 4, which are substantially at right angles to the bottom, and these sides are preferably given a flare at the top,

as shown at 5. I wish it to be understood, however, that I do not desire to be limited to this particular shape of rib, and while I deem it the best shape it could be varied widely 50 without departing from my invention. Preferably these ribs are arched, as shown, to increase their carrying power. Spanning the space between the U-shaped ribs are the plates 7. The plates 7 have their side edges 55 8 turned down to engage with the open side of the U-shaped ribs. When in position, the downturned edges 8 fit snugly against the sides 4 of the U-shaped ribs. These spanning-plates are arched in the direction of their length when they are used in connection with arch-shaped ribs. The space in the U-shaped ribs between the ends of the cover-plates is preferably filled with concrete 9 or other fireproof material. This concrete may 60 be and preferably is extended over practically the entire surface of the cover-plates, so as to present a smooth surface to lay the floor upon. By this construction it will be seen that the entire weight of the floor rests 65 directly on the U-shaped ribs. These ribs are only supported at their end by the I-girders, and these ribs must therefore be necessarily made of sufficient strength to withstand any strain that may be put upon them. 75

While I have shown and described what I deem to be the preferred form of my invention, it is to be understood that many changes could be made therein without departing from the spirit of my invention. 80

While I have described this construction in connection with fireproof floors, I desire it to be understood that the construction is applicable to decks of vessels, arches of sewers, roofs for tunnels or buildings, sidewalks over vaults, or in any other place where it might be found desirable. 85

Having thus described my invention, what I claim as new, and desire to secure by Letters Patent, is—

In a floor construction the combination with girders of two series of arched ribs, arching

the space between the girders, one series being concave in cross-section, and being located parallel to each other, the concave surface forming the upper surface of the arch, the second series of arched ribs being also concave in cross-section, the concave surface forming the under side of the arch, the two series of arched ribs interlocking with each other, and

the whole surface above the arch being filled and covered with concrete.

Signed by me at city of Baltimore, State of Maryland, this 13th day of May, 1901.

THOMAS A. NAYLOR.
